[57] **CLAIM**

The ornamental design for switch guard, as shown and described.

DESCRIPTION

FIG. 1 is a perspective view as seen from the top front and left side of the switch guard showing my invention.

FIG. 2 is a top view thereof;

FIG. 3 is a bottom view thereof;

FIG. 4 is a left side view thereof;

FIG. 5 is a right side view thereof;

FIG. 6 is a rear elevational view thereof; and,

FIG. 7 is a front elevational thereof.

The broken line showing of an electrical switch plate and fasteners is for illustrative purposes only and forms no part of the claimed design.
